UNITED STATES PATENT OFFICE.

ALEXANDER S. RAMAGE, OF DETROIT, MICHIGAN, ASSIGNOR TO INTERNATIONAL COLOR & CHEMICAL COMPANY, INCORPORATED, OF DETROIT, MICHIGAN, A CORPORATION OF NEW YORK.

PROCESS OF RECOVERING SUCROSE FROM SOLUTIONS.

No Drawing.

Application filed March 18, 1920. Serial No. 366,939.

To all whom it may concern:

Be it known that I, ALEXANDER S. RAMAGE, a citizen of the United States, residing at Detroit, in the county of Wayne and State 5 of Michigan, have invented certain new and useful Improvements in Processes of Recovering Sucrose from Solutions, of which the following is a specification.

This invention is a novel process for the 10 separation and recovery of sucrose from impure solutions, and particularly from cane molasses, whether derived from the refining of raw sugar or directly from the cane syrups. According to the invention the sucrose 15 is precipitated as lead sucrate by direct reaction with lead hydroxid in excess, and the mixed precipitate thus obtained is treated in such manner as to yield on the one hand a sucrose solution wholly free from lead, and on the other hand a lead hydroxid suitable for use in a continuation of the process. The process is therefore essentially 20 cyclical in character, in that the lead compounds are quantitatively regenerated.

As is well known cane molasses contains 25 considerable proportions of reducing sugars commonly termed glucose. I have found that glucose cannot be quantitatively precipitated by lead oxid or hydroxid as lead glucosate, except at temperatures below about 5° C. At temperatures higher than this I find that the glucose is decomposed by lead hydroxid into soluble lead products, amounting at 20° C. to about 20-30%, and 30 at 100° C. practically all of the glucose disappears. The products formed also change according to the temperature used. If the temperature has been kept below 60° C. the principal products appear to be lead salts 35 of saccharic lactone and glucinic lactone, these salts decomposing rapidly upon standing to the corresponding lead salts of saccharic and glucinic acids. These lead salts are largely precipitated on 10-12 hours 40 standing.

At temperatures between 60-100° C. the principal products formed on standing are the lead salts of saccharic and lactic acids. If the precipitate produced by addition of 45 the lead hydroxid to a glucose solution is washed, and then carbonated at about 60° C., it is still further decomposed leaving insoluble lead salts of its oxidation products. The decomposition proceeds to such extent

that usually only from 10-20% of the original glucose can be recovered in the solution after carbonation.

Furthermore the lead precipitate left from carbonation presents the peculiarity of forming in the filter presses a very firm cake, 60 containing about 25% of water, which however upon rubbing quickly turns to a thin paste. On heating to 150° C. this product starts to decompose, and at about 200° C. its lead content is reduced to finely divided 65 spongy lead which catches fire in presence of air. The proportion of organic matter contained in this lead precipitate is approximately 10-12%.

The molasses from refining raw sugars 70 generally contains around 20-24% glucose and 18-22% sucrose, together with some acid products derived from fermentation. The final molasses from sugar cane, when fresh, usually contains about 30-34% sucrose with 18-20% glucose.

While my invention is not limited to the employment of any specific proportions of lead hydroxid, I find it to be good practice to use lead hydroxid in the proportion of approximately 1.8 times by weight of the glucose present, plus 2.5 to 3 times the sucrose content. In addition allowance may also be made for any free acids which may be present.

Following is a specific illustration of my process, it being understood, however, that the invention is not limited to the employment of the precise proportions mentioned by way of illustration, or to the exact operating conditions hereinafter detailed.

2600 pounds of cane molasses containing about 20% of glucose and 22% of sucrose is diluted with 25% of water and thoroughly agitated with a paste containing 2700-2800 95 pounds of lead hydroxid (PbO_2H_2). The agitation is continued until the mass acquires a semi-solid consistence, after which it may be allowed to stand for a few hours in order to complete the reaction. This precipitation may be carried out at normal or higher temperatures, up to about 70° C. At the conclusion of the reaction sufficient cold water is added to transform the mass into a pulp which is then pumped to the filter 105 presses.

The mother liquor or filtrate contains the non-precipitatable contents of the molasses,

including the mineral salts, as well as soluble lead compounds of the oxidation products of glucose. It may be run into a tank where sufficient milk of lime is added to 5 render the solution alkaline, and carbon dioxid is passed through, preferably at about 60° C., until all of the lead is precipitated. The resulting lead precipitate is filtered off and returned to the process, being preferably 10 combined with the lead precipitate derived from the carbonation to be described below.

The lead precipitate from the molasses, after thorough washing with cold water, consists essentially of lead sucrate, more or 15 less lead glucosate according to the temperature of precipitation, some excess of lead hydroxid, and any precipitatable non-sugars. This is suspended in a liquid bath, preferably a dilute syrup from a previous 20 operation, and is carbonated therein, preferably at about 70° C., the passage of the carbon dioxid being continued just so long as the polarization of the liquid increases, that is to say, so long as sucrose and glucose 25 continue to be set free. At the completion of this operation the precipitate is filtered out, yielding a filtrate which consists essentially of a sucrose solution, containing some glucose, and containing also some soluble 30 lead compounds of the oxidation products of glucose; and a precipitate which, as regards its metallic salt contents, is essentially a basic carbonate of lead, corresponding more or less closely according to the operating 35 conditions to the formula $2\text{PbCO}_3 \cdot \text{PbO}_2\text{H}_2$, together with insoluble lead compounds of saccharic and glucinic acids, and other insoluble organic compounds containing 40 lead. The basic carbonate under ordinary conditions may comprise some 60-70% by weight of the dried precipitate.

The sucrose-bearing solution obtained as above is agitated with sufficient lime to precipitate the whole of its lead content, and is 45 heated to about 70° C. for one-half hour, then carbonated to faint alkalinity and filtered. The filtrate is then concentrated, and is preferably again limed and carbonated as is the practice in the treatment of beet 50 juice; and is carefully tested for lead. The lead-free solution may advantageously be treated at this point with animal charcoal or other decolorizing carbon, which would of course serve to remove any traces of lead 55 which might escape the previous precipitating step. From this solution the sucrose can be directly recovered in merchantable form by the usual crystallization methods.

The lead bearing precipitate from the carbonating step is re-converted into the hydroxid for re-use in the process. This is 60 preferably done as follows:

The basic carbonate from several batch operations as above described is distributed 65 to a series of wooden tanks each provided

with an agitator, each tank receiving approximately 3000 pounds dry weight of the precipitate. To the precipitate in the first tank I add an excess of caustic soda above the amount theoretically required to convert 70 the carbonate component into hydroxid. In practice I find it desirable to introduce the caustic soda in the form of a 5-10% solution, and in quantity equivalent to a 30-50% excess above the theoretical proportions above 75 mentioned. The reaction proceeds more rapidly at temperatures above normal and in practice I prefer to agitate the mass at a temperature of about 70-80° C. for a period of approximately one hour. At the end of 80 this time the solid contents of the tank consist substantially of lead hydroxid, and may be separated from the solution, washed, and utilized directly in a repetition of the molasses-treating step of the process, precisely 85 as described above.

The solution contains sodium carbonate, together with approximately 10% of the lead content of the first tank, in the form of sodium plumbite usually with some excess 90 of uncombined caustic soda and the whole of the organic non-sugars. This solution is brought into presence of the basic carbonate in the second tank, and is agitated therewith in the cold. Thereby the sodium plumbite is decomposed, its lead content being precipitated in the form of lead hydroxid. Any excess of caustic soda contained in the solution, together with that liberated by the decomposition of the plumbite, reacts upon 95 the basic lead carbonate in the second tank to convert the same into hydroxid. The solution resulting from this treatment should consist essentially of sodium carbonate and organic substances, but as a matter of precaution, it may be introduced into presence 100 of the basic carbonate in the third tank in series, and agitated therewith, in order to remove any traces of caustic soda or plumbite which may be present; or the solution 105 containing free alkali and lead may be carbonated if desired, thereby converting its lead and caustic alkali contents into basic lead carbonate and sodium carbonate respectively. This solution is then withdrawn, and may be causticized with lime in 110 the usual manner, yielding caustic soda, which returns to the cycle at the appropriate point, and a lime mud containing the organic matters.

The contents of the second tank, which by the above treatment have been partially converted into hydroxid, are then treated with caustic soda in excess precisely as above described with reference to the contents of the first tank in series; and the resulting hydroxid used in the sucrose precipitation. It will be understood of course that in computing the excess of caustic soda to be used in the treatment of the second tank, due allow- 115 120 125 130

ance must be made for the conversion of carbonate to hydroxid which has already occurred through the action of the mother liquor. If the liquor from the first tank has 5 been carbonated instead of being utilized in the second tank, the resulting basic carbonate of lead is at once filtered off and returned to the process, while the carbonate of soda containing the organic non-sugars 10 is causticized with lime as above.

In carbonating the sucrate precipitate in order to set free the sucrose, it is desirable to avoid continuing the passage of the carbon dioxid after the polarization value of 15 the liquid has ceased to rise, since under these conditions organic matters other than sucrose which may have been carried down by the precipitated mass pass again into the sucrose solution. It is desirable that such 20 organic matters should be retained by the precipitate at this stage, since they are dissolved therefrom in the subsequent treatment with caustic soda, and pass ultimately into the lime mud resulting from the re- 25 causticizing step of the process.

All of the plant washings, whether from the treatment of beet or cane sugar products, should be examined for lead; and in case it is found to be present in material quantities, these washings should be subjected to 30 carbonation preferably at about 70° C., to separate the precipitate and recover the lead. The same caution applies also to the mother liquors from the lead sucrate precipitation. 35

I claim:—

1. A cyclical process of recovering sucrose from crude solutions thereof containing also glucose, comprising adding to such 40 solutions lead hydroxid in sufficient excess to precipitate the sucrose together with non-sucrose substances; separating the precipitate from the mother liquor and liberating the sucrose content of the precipitate by 45 limited carbonation; thereby forming a sucrose-bearing solution containing soluble lead compounds and a residual precipitate containing non-sucrose substances; separat-

ing the sucrose-bearing solution from the residual precipitate and eliminating lead 50 from the sucrose-bearing solution by means of lime; treating the residual precipitate containing non-sucrose substances with an alkali hydroxid in excess, thereby dissolving non-sucrose material, and converting the bulk of 55 the lead-content of the said precipitate into hydroxid; separating the resulting lead hydroxid from the alkaline solution containing non-sucrose material; and introducing said lead hydroxid in excess into a further quantity of the crude sucrose-bearing 60 solution in a succeeding cycle of the process.

2. A cyclical process of recovering sucrose from crude solutions thereof containing also glucose, comprising adding to such solutions 65 lead hydroxid in sufficient excess to precipitate the sucrose together with non-sucrose substances; separating the precipitate from the mother liquor and liberating the sucrose content of the precipitate by limited carbonation, thereby forming a sucrose bearing solution containing soluble lead compounds 70 and a residual precipitate containing non-sucrose substances; separating the sucrose-bearing solution from the residual precipitate and eliminating lead from the sucrose-bearing solution by means of lime; treating the residual precipitate containing non-sucrose substances with an alkali hydroxid in excess, thereby dissolving 75 non-sucrose material and converting the bulk of the lead-content of the said precipitate into hydroxid; separating the resulting lead hydroxid from the alkaline solution containing non-sucrose material; introducing said lead hydroxid in excess into a further quantity of the crude sucrose-bearing 80 solution in a succeeding cycle of the process; and recovering the excess of alkali hydroxid, together with its content of dissolved 85 lead from the alkaline solution containing non-sucrose material, by reacting thereon with an excess of the lead-bearing precipitate resulting from the carbonation.

In testimony whereof, I affix my signature. 90
